UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

THREAD TRIMMER FOR SEWING MACHINES.

Application filed April 15, 1922. Serial No. 552,926.

To all whom it may concern:

Be it known that I, JOHN KIEWICZ, a citizen of the United States, and residing at Boston, county of Suffolk, State of Massachusetts, have invented an Improvement in Thread Trimmers for Sewing Machines, of which the following description, in connection with the accompanying drawing, is a specification, like characters on the drawing representing like parts.

This invention relates to sewing machines of the type adapted to sew a short seam and then come to rest and particularly to a thread trimming device arranged to trim the thread at the end of the seam. The thread trimmer is of that known type which is constructed to cut the thread at the end of the seam and to hold the needle thread until after the stitching on the next seam has begun and then to cut the thread fragment which has been engaged by the thread holder thus leaving the thread which is trimmed closely to the work at both ends of the seam.

One feature of the invention relates to a novel thread trimming means which is controlled by the stop motion by which the sewing machine is brought to rest at the end of the seam.

In the sewing machine herein illustrated the driving mechanism therefor comprises a fast pulley and a loose pulley with a belt shipper for shifting the driving belt from one pulley to the other, and one feature of the invention relates to a thread cutting device which is actuated from the loose pulley after the driving belt has been shifted onto it at the finish of the seam.

Another feature of the invention relates to a thread cutter for a two-thread sewing machine which is provided with means for cutting both the upper thread above the work and the under thread beneath the work, both of which cutting devices are controlled by the stop motion and are actuated by the rotation of the loose pulley after the driving belt has been shifted onto it.

Another feature of the invention relates to a thread trimming device which is arranged to cut the thread twice, once at the end of the seam and again after the next seam has been started, the second cutting

being for the purpose of trimming the thread fragment held by the holding means.

Other features of my invention relate to various improvements in thread cutting devices all as will be more fully hereinafter set forth.

In order to give an understanding of the invention I have illustrated in the drawings a selected embodiment thereof which will now be described after which the novel features will be pointed out in the appended claims.

Fig. 1 is a side view of a sewing machine having my improved thread trimmer applied thereto.

Fig. 2 is an under side view of the bed plate of the sewing machine with some of the sewing machine parts omitted.

Fig. 3 is an end view of the head.

Fig. 4 is a fragmentary view of the cutter actuating mechanism.

Fig. 5 is a top plan view of the part shown in Fig. 4.

Fig. 6 is a fragmentary view of the latch for operatively connecting the parts to the loose pulley.

Fig. 7 is a top plan view of the clamp plate with the upper thread trimmer.

Fig. 8 is a side view thereof looking from the top of the sheet.

Fig. 9 is an under side view of the part shown in Fig. 8.

Fig. 10 is a view showing the under thread trimmer.

Fig. 11 is an under side view of the plate shown in Fig. 10.

Fig. 12 is a section on the line 12—12, Fig. 11.

Fig. 13 is a section on substantially the line 13—13, Fig. 5.

Fig. 14 is a detail of the latch 56.

Figs. 15, 16 and 17 are views showing the position of the parts comprising the upper thread cutter at different points in the cycle of operations.

Fig. 18 is a modified form of the slide for pulling off the under thread and drawing it against the knife.

Fig. 19 is a detail view of the means for relieving the clamping pressure on the work after the thread-trimming operation is completed.

Fig. 20 is a detail of the arm 36.

I have illustrated the invention herein as it might be applied to a sewing machine having some of the features illustrated in 5 United States Patents No. 749,776, Jan. 19, 1904, No. 1,088,652, Feb. 24, 1914, and No. 1,402,073, Jan. 3, 1922.

I desire to have it understood, however, 10 that the invention is not limited to use in connection with sewing machines such as shown in these patents but may be equally well embodied in other types of sewing machines.

The sewing machine herein illustrated 15 comprises a bed 1 which is pivotally supported on a base 2 and which carries an overhanging arm 3 that supports the vertically-reciprocating needle bar 4, the latter supporting the usual needle 5. The work 20 in which the short seam is to be sewed, is retained in place by a suitable work-holding means comprising a clamp plate 6 that is 25 slidable back and forth in ways 7 formed in the bed 1, and two work clamps 8 and 9 which operate to clamp the work to the clamp plate 6.

The sewing machine herein shown is of 30 the two-thread type and it embodies in its construction a bobbin carrier or shuttle situated beneath the work clamp and a rotary hook for carrying the loop of needle thread around the shuttle, as usual in two-thread sewing machines. The shuttle and rotary hook are not illustrated in detail as they 35 may have any suitable or usual construction but are shown generally at 10. The needle and the hook are both operated from a driving shaft 11 which is journaled in the bed plate 1. The connections between the driving 40 shaft 11 and the needle bar 4 are or may be all as shown in the above-mentioned patents and, therefore, do not need to be described herein.

The rotary hook is driven from the shaft 45 12, which is connected by bevelled gears 13 with a cross shaft 14, the latter being connected by bevelled gears 15 with the driving shaft 11. These gears are constructed to cause the hook to rotate in proper timed 50 relation with the reciprocations of the needle.

The driving means herein shown for actuating the driving shaft comprises a driving belt 16 and fast and loose pulleys 17 and 55 18, the pulley 17 being fast on the driving shaft 11 and the pulley 18 constituting a loose pulley. The machine is started by shifting the belt 16 from the loose pulley 18 to the fast pulley 17 and is stopped by shifting the belt from the fast to the loose pulley. The belt is shifted by a belt shipper 19 and the operation of the latter is controlled by a stop motion operating somewhat similar to that illustrated in the above-mentioned 60 65 patents. This stop motion comprises a bracket

arm 20 carried on a rock shaft 21 which is 70 slidable longitudinally and is subject to the action of a spring 22 tending to move it longitudinally toward the right Fig. 2. This bracket arm 20 carries an extension 23 which 75 engages the belt shipper 19 so that when the bracket arm 20 and the rock shaft 21 are moved to the right Fig. 2 under the influence of the spring 22 the belt 16 will be shifted from the fast to the loose pulley. The stop 80 motion also includes a stop cam 24 fast on the driving shaft 11 and co-operating with a dog 25 slidably mounted in the bracket arm 20 and acted on by a spring 26. The bracket arm 20 is also acted on by a spring-pressed 85 plunger 27 which tends to hold it in the position shown in Fig. 4, said plunger having the spring 28 associated therewith which resists upward movement of the plunger 27.

When the sewing machine is running the bracket arm 20 will be in the dotted line position Fig. 1, and in this position the stop dog 25 is on the inside of the stop cam 24 and is free therefrom. At the end of the sewing operation the catch or trip holding the stop motion in its inoperative position is released and the spring 22 acts to shift the rock shaft 21 and the bracket arm 20 towards the right Figs. 1 and 2 into a position where the stop dog 25 comes in the path of the stop cam 24, which is turning in the direction of the arrow in Fig. 4. This stop cam has the rise 29, the valley 30 beyond the rise, and the stop face 31 at one side of the valley. When the shaft 21 with its bracket arm has been shifted into the position shown in Fig. 2 the stop dog 25 comes onto the lower portion of the stop cam 24 and as the cam rotates the high portion 29 of the cam passes under the stop dog thereby swinging the bracket arm 20 upwardly about the rock shaft 21 and against the action of the spring 28. The resistance of the spring 28 serves as a brake to check the momentum of the parts and as the stop dog passes over the high point 29 of the cam and drops into the valley 30 it will meet the stop face 31 of the stop cam, thus bringing the parts to rest. Since the stop dog is backed by the spring 26 the impact of the face 31 against said stop dog will compress the spring 26 slightly thus giving a cushioned stopping movement.

It will be remembered that the bracket arm 20 has the extension 23 which engages the belt shipper 19 and hence the movement of the bracket arm 20 and rock shaft 21 from the dotted line position Fig. 1 into the full line position will operate through the extension 23 to shift the belt 16 from the fast to the loose pulley, and after the belt has been thus shifted onto the loose pulley the stop cam operates to bring the machine to rest at a predetermined point in the cycle of operations, all as usual in machines of this type.

The parts thus far described are, or may be, all as usual in sewing machines of this type and in many respects are similar to the constructions illustrated in the above-mentioned patents.

One feature of the present invention relates to a thread cutter for the upper thread which is controlled by the stop motion and which is actuated by the loose pulley 18 after the driving belt has been shifted onto it. Another feature of the invention is an under thread cutter similarly controlled and actuated.

The upper thread cutter is associated with the work clamp and is indicated at 32. It is in the form of a blade having a cutting edge 33 and carried by a lever 34 pivoted at 35 on a resilient plate or arm 36 secured at its rear end to the clamp plate 6 and at the forward end 161 extending beneath the clamp 8. The cutting edge 33 of the cutter operates directly beneath the work clamp 8 and at the end of each sewing operation, the lever 34 is swung into the position shown in Fig. 17 thereby to sever the thread. The means for operating the cutter 32 will be presently described.

Associated with the thread cutter is a thread gripper 37 in the form of a hook which is carried at the end of a lever 38 pivoted at 39 to the arm 36. This gripper operates just above the end 161 of the arm 36 and between the latter and a spring gripping plate 40.

The machine herein shown is adapted to sew buttonholes and in the operation thereof the clamp plate 6 has a feeding movement first in one direction and then in the other to feed the work for the formation of the stitches along first one side and then the other of the buttonhole. At the beginning of the buttonhole the parts are in the position shown in Fig. 15, and as the stitching begins the work clamp moves to the left so as to form the stitching down one side of the buttonhole slit 46 and when said side has been completed the clamping plate is fed in the opposite direction so as to cause the stitching to be formed down the other side of the buttonhole slit. During the stitching on the latter side of the buttonhole and when the parts are in approximately the position shown in Fig. 16 the thread gripper 37 is moved into the position shown in Figs. 7 and 16 and is locked in this position by a suitable spring-pressed latch 47 which engages the tail 48 of the lever 38, said latch being acted upon by a spring 49. The gripper remains in this position until the buttonhole is completed as shown in Fig. 17 and at this time the latch 47 is released thus allowing the spring 50 to return the gripper to the position shown in Fig. 17 and during this movement it will engage the needle thread *r* between the

needle 5 and the cutter and will draw the needle thread into gripping engagement with the spring plate 40. Subsequent to this operation the cutter 32 is given a movement into the position shown in Fig. 17 thereby to cut the thread between the work clamp and the work.

The movement of the thread gripper 37 from the position shown in Fig. 15 to that shown in Fig. 16 is secured by or through the feeding movement of the work clamp, and the release of the thread gripper to permit it to return to the position shown in Fig. 17, and the operation of the cutter are controlled and determined by means associated with the stop mechanism.

The thread gripping arm 38 has a pin or projection 139 rising therefrom which is acted upon by a cam 138 carried by the end of a lever 137 pivoted at 136 to the overhanging arm 3. The upper end of the lever 137 is acted on by a spring 135 which yieldingly holds it in the position shown in Fig. 3 against the stop 134. The cam 138 has the shape shown in dotted lines Fig. 7 and it normally stands in the path of the projection 139.

When the work clamp is moving in the direction of the arrow in Fig. 15 thereby to stitch down one side of the buttonhole the projection 139 will engage the cam 138 and will swing the lower end of the lever to the right Fig. 3 against the action of the spring 135. On the other hand when the clamp plate 6 is moving in the opposite direction or in the direction shown by the arrow Fig. 16 thereby to form the stitches on the other side of the buttonhole and when the parts arrive at about the relative position shown in Fig. 16, the cam 138 engages the stop 139 and because the lever 137 is prevented from swinging to the left Fig. 3 by the stop 134 this engagement of the cam with the projection 139 will swing the lever 38 into the position shown in Figs. 7 and 16, that is, it will carry the hook end 37 of said lever across the line of stitching and to the opposite side of the needle thread. In Fig. 7 the cam 138 is shown as just passing the projection 139 after having swung the lever 38 to carry the hook 37 across the line of stitching and when said lever has been thus turned the latch 47 will automatically engage the end 48 of the lever thereby retaining said lever in this position after the cam 138 passes the projection 139 and until the latch is released at the end of the buttonhole as will be presently described. In Figs. 15, 16 and 17 the sewing opening through the throat plate and through which the needle reciprocates is shown in dotted lines at 150.

The lever 34 carrying the cutter is pivotally connected at 43 to the end of another lever 41 which in turn is pivoted at 42 to

the arm 36, the lever 41 being provided with a cam face 44.

The latch 47 is also provided with a cam face 51 and these two cam faces are arranged to be acted on by an actuating finger 45. This finger is mounted on a rod 52 that is slidably carried in a bracket 53 secured to the overhanging arm 3 and said arm 45 depends from the rod and is so situated that when the sewing on the buttonhole is completed and the clamp plate is in the position shown in Fig. 17 said finger will occupy the dotted line position in Fig. 7.

After the stitching mechanism comes to rest the finger 45 is given a movement to the right Fig. 7 thereby first tripping the latch 47 to allow the thread gripper to operate and subsequently acting against the cam 44 to cause the cutter to operate.

The actuating finger 45 is given its movement from the loose pulley 18 after the belt has been shifted thereto by the following mechanism. The extension 23 of the bracket arm 20 by which the belt shipper is operated has secured thereto an arm 54 on which is pivotally mounted at 55 a latch 56, the latter being acted upon by a spring 57.

58 designates a rock shaft which is journaled in the frame and is journaled at one end in a bracket arm 59 and which has fast thereto an arm 60 which is situated outside of the loose pulley 18 and which carries a pin 61 that is adapted to engage in a spiral thread 62 formed on a hub 63 of the loose pulley. This arm is normally held in elevated position with the pin 61 above the spiral thread 62 by means of a spring 64 which is connected at one end to the frame and at the other end to a depending arm 65 fast on the rock shaft 58.

66 indicates a stop against which the arm 65 is normally held by the spring 64. The rock shaft 58 not only can turn in its bearing but can also slide longitudinally thereof. It will be remembered that after the belt has been shifted onto the loose pulley the stop dog 25 is brought into position to be engaged by the stop cam 24 and as the stop cam rotates the high point 29 thereof will swing the bracket arm upwardly against the action of the spring 28 just before the stop dog drops into the valley 30.

Since the arm 54 is carried by the extension 23, said arm will also have a rising movement when the stop dog is passing over the high point 29 of the cam and during such rising movement the latch 56 will be carried above the arm 60 and will be automatically latched thereto as shown in Fig. 14. As a result when the stop dog drops into the valley 30 the downward movement of the latch 56 draws the arm 60 downwardly and brings the pin 61 into the spiral groove 62.

It will be remembered that the screw 69 thread 62 is rigid with the loose pulley 18

and hence as soon as the belt 16 is thrown onto the loose pulley the screw will be rotated. When the arm 60 is drawn down by the latch 56 thereby to bring the pin 61 into mesh with the spiral groove 62, the rotation of the screw 62 will operate through the pin 61 to move the arm 60 away from the loose pulley 18 and since the arm is fast to the shaft 58 it follows that said shaft will be moved in the direction of its length and into the dotted line position Fig. 5. This movement of the shaft 58 is transmitted to the rod 52 thereby giving the operative movement to the actuating finger 45. For this purpose the rod 52 is formed with the extension having the downwardly bent portion 68 and the backwardly bent portion 69 and this backwardly bent portion carries a projection 70 which is adapted to be engaged by a block 71 fast on the shaft 58. Hence the movement of the shaft 58 given to it by the screw 62, will operate through the parts 70, 71 to move the rod 52 to the right Fig. 1, and this movement will cause the actuator 45 to engage the cam faces 51 and 44 successively thereby causing the gripper 37 to grip the needle thread and then the cutter 32 to cut said thread.

The rod 52 is acted on by a spring 171, which is confined between the arm 45 and a portion of the bracket 53, said spring tending to return the rod to its normal position shown in Fig. 1.

The construction herein shown is such that when the shaft 58 has been given its desired movement by the screw 62 the latch 56 will be automatically disengaged from the arm 60 thus allowing the latter to be returned to its normal position by the spring 64. This spring is so disposed that it not only tends to turn the shaft 58 about its axis but also tends to draw the shaft longitudinally toward the frame, and, therefore, as soon as the latch 56 is disengaged from the arm 60 the spring 64 will restore said arm to its normal position.

This automatic release results from the swinging movement of the latch 56 due to the movement of the arm 60 away from the loose pulley 18. As the screw 62 moves the arm 60 it will force the latch 56 backwardly into the dotted line position shown in Fig. 6, and when the latch reaches the inclined position shown the arm 60 will automatically slip off from the shoulder 73 of the latch and will be returned to normal position.

The latch is shown as having a stop screw 74 adjustably mounted therein, the adjustment of which will determine the position at which the arm 60 will be automatically disengaged from the latch.

I have also provided herein means for cutting the under thread beneath the work which is actuated by the loose pulley 18.

Such under thread cutter is shown in Figs. 10, 11 and 12 and it comprises a cutting blade 75 fast on a cover plate 76 secured to the clamp plate 6 and on which the work 5 rests.

Associated with this cutter 75 is a slide 77 having at one end a head 78 that is provided with a slot 79 and a thread engaging finger 80 entering the slot. The slide is 10 normally in the position shown in Fig. 10 but at the end of the buttonhole it is moved forwardly into the position shown in Fig. 11 (which is an under side view of Fig. 10) and during this movement the under thread 15 *t* leading to the work from the shuttle enters the slot 79. The slide is then returned to the position shown in Fig. 10 and during its movement the under thread is caught by the finger 80 and is carried against the cutting edge 82 of the cutter 75 thereby cutting the thread. The severed end of the thread leading to the supply is held clamped between the finger 80 and the head 78 of the plate 76.

20 The movement of the slide from the position shown in Fig. 10 to that shown in Fig. 11 is derived from the screw thread 62 and the movement in the opposite direction is derived from a spring 83 which 25 is connected at one end to the plate 76 and at the other end to said slide. For thus moving the slide I have provided a rod 84 which is slidably mounted in bearings 85 carried by the bed plate and has its end 30 provided with a depending finger 86 which is adapted to be engaged by an arm 87 pivoted to the frame at 88 and extending through a notch 89 formed in the block 71. Consequently as the shaft 58 is moved by 35 the screw 62 the arm 87 will be swung into the dotted line position Fig. 5 and the end 40 of the arm will engage the projection 86 and thus slide the rod 84 longitudinally.

45 This rod 84 has an arm 90 fast thereon which is adapted to engage the projection 91 depending from the slide 77, the construction being such that movement of the rod 84 to the right Fig. 2 will cause the arm 90 to engage the projection 91 and move 50 the slide into the position shown in Fig. 11. As soon as the arm 90 is disengaged from the screw 62 then the spring 83 will return the slide to its position thus cutting the under thread, and the rod 84 will be returned 55 to its normal position by the return spring 91.

In Fig. 18 I have shown a little different embodiment of the under thread cutter wherein the slide 77 is formed with a relatively shallow notch 92 and with a relatively short thread-actuating finger 93. In this embodiment the movement of the slide into the position shown in Fig. 11 will cause the under thread to enter the notch 92 and the thread will engage the bottom

of the notch before the slide completes its outward movement so that during the final outward movement the slide will act on the thread and draw off a length of thread from the bobbin. When the slide is released 70 and returns to the position shown in Fig. 10 the finger 93 will engage the thread and draw it against the cutting edge 82 of the knife 75 thus cutting the under thread close 75 to the work.

It is desirable that the cutting of the thread should occur before the work is unclamped because the cutting can be better accomplished when the work is held by the clamp. In sewing machines of this type 80 the work is usually automatically released when the machine is brought to rest. In the present invention I have provided means for holding the work clamped after the machine has come to rest and until after the 85 upper thread has been severed. This is accomplished by providing the arm 36 with a boss 140, and by providing a hold down 141 carried by a bracket 142 secured to the overhanging arm 3, which hold down is so 90 situated that when the clamp plate completes its feeding movement and comes to rest at the end of the buttonhole the boss 140 is positioned underneath the hold down 141 and in engagement therewith. 95

It will be remembered that the end 161 of the arm 36 underlies the clamp 8 and, therefore, when the clamp 8 is depressed to clamp the work it forces the end 161 of the arm 36 and forces the latter down in contact with 100 the work. At the end of the sewing operation the work clamps 8 and 9 are automatically raised but because of the engagement of the post or boss 140 with the hold down 141 the arm 36 will be retained in its 105 clamping position, thus holding the work while the thread is being severed.

In Fig. 20 I have illustrated the position of the parts after the work clamps have been released but while the arm 36 is still retained in clamping engagement with the work by the hold down 141. 110

This hold down is disengaged from the boss 140 by the movement of the rod 52 and for this purpose said rod is formed at its 115 end with a hook 143 adapted to engage the hold down 141 just as the rod 52 completes its movement to the right Fig. 1. The hold down 141 is made resilient or flexible so that when the hook 143 engages it it will deflect 120 it and withdraw its end from the boss 140 thereby allowing the arm 36 to release the work. This releasing of the work by the arm 36, however, does not occur until after the upper thread has been cut as above described. 125

I have described above the operation involved in cutting the thread at the end of the buttonhole and when this operation is completed the end 162 of the upper thread 130

r will be held by the thread gripper 37, as indicated in Figs. 1 and 3. When the sewing begins on the next buttonhole this end 162 will still be retained by the thread gripper 5 thus holding the end of the needle thread so that the first stitches will be properly formed. The end 162 remains held by the thread gripper while the stitching is being carried down one side of the buttonhole and 10 back along the other side of the buttonhole until the parts arrive at the position shown in Fig. 16 at which time the thread gripper is moved across the line of stitching thereby releasing the thread end 162.

15 The mechanism herein shown is designed so that it will cut this thread end 162 before it is released by the gripper so that the thread at both ends of the seam is trimmed close to the work. This second cutting 20 operation is performed by the cutter 32 and results from the feeding movement of the clamp plate in the direction of the arrow Fig. 15 and while the stitching is being formed down the first side of the buttonhole 25 slit. When the stitching on the buttonhole begins the arm 45 has approximately the position relative to the cam face 44 shown in Fig. 7 and as the clamp plate 6 moves toward the left Fig. 7 or in the direction of the arrow in 30 Fig. 15 for the purpose of sewing down one side of the buttonhole the cam face 44 will engage the arm 45 thereby actuating the cutter and cutting the thread fragment 162 close to the work. The thread-trimming device, therefore, cuts the needle thread at the 35 end of the seam and holds the thread until the next stitch is started after which it operates again to cut the end of the needle thread which has been held by the thread 40 gripper thus leaving the buttonhole completely trimmed at both ends of the seam.

While I have illustrated some selected embodiments of my invention I do not wish to be limited to the constructional features 45 shown.

I claim:

1. In a sewing machine of the type adapted to sew a short seam and then come to rest, the combination with stitch-forming mechanism including a reciprocating needle, of a stop motion for bringing the machine to rest at the end of the sewing operation, and means controlled by the stop motion but actuated independently thereof for cutting 50 the needle thread at the end of the sewing operation and after the machine has come to rest.

2. In a two thread sewing machine of the type adapted to sew a short seam and then come to rest, the combination with stitch-forming mechanism to concatenate an upper and an under thread, of a stop mechanism to bring the machine to rest at the end of the sewing operation, and means controlled 60 by the stop motion but actuated independ-

ently thereof to cut the upper and under thread after the machine has come to rest.

3. In a sewing machine of the type adapted to sew a short seam and then come to rest, the combination with stitch-forming mechanism including a needle, of driving mechanism for the machine comprising a driving belt, a fast pulley from which the machine is operated and a loose pulley, means to shift the belt from the fast to the loose 70 pulley at the end of the sewing operation, and means actuated by the loose pulley to cut the thread.

4. In a sewing machine of the type adapted to sew a short seam and then come to rest, the combination with stitch-forming mechanism including a needle, of driving mechanism for the machine comprising a driving belt, a fast pulley from which the machine is operated and a loose pulley, means to 80 shift the belt from the fast to the loose pulley at the end of the sewing operation, and means actuated by the loose pulley to cut the thread above the work.

5. In a sewing machine of the type adapted to sew a short seam and then come to rest, the combination with stitch-forming mechanism including a needle, of driving mechanism for the machine comprising a driving belt, a fast pulley from which the machine is operated and a loose pulley, means to 90 shift the belt from the fast to the loose pulley at the end of the sewing operation, and means actuated by the loose pulley to cut the thread beneath the work.

6. In a sewing machine of the type adapted to sew a short seam and then come to rest, the combination with stitch-forming mechanism including a needle for manipulating an upper thread, an under thread mechanism, driving means for the machine comprising a driving belt, a fast pulley connected to the operative parts of the machine and a loose pulley, means to shift the belt from the fast to the loose pulley at the end of the sewing operation, and means actuated by the loose pulley after the belt is shifted to cut the upper thread above the work 100 and to hold the cut end.

7. In a sewing machine of the type adapted to sew a short seam and then come to rest, the combination with stitch-forming mechanism including a needle for manipulating an upper thread, an under thread mechanism, driving means for the machine comprising a driving belt, a fast pulley connected to the operative parts of the machine and a loose pulley, means to shift the belt from the fast to the loose pulley at the end of the sewing operation, and means actuated by the loose pulley after the belt is shifted 110 to cut the under thread beneath the work and to hold the cut end.

8. In a sewing machine of the type adapted to sew a short seam and then come to rest, 120

the combination with stitch-forming mechanism including a needle for manipulating an upper thread, an under thread mechanism, driving means for the machine comprising a driving belt, a fast pulley connected to the operative parts of the machine and a loose pulley, means to shift the belt from the fast to the loose pulley at the end of the sewing operation, and means actuated by the loose pulley after the belt is shifted to cut both the upper thread above the work and the under thread beneath the work.

9. In a sewing machine of the type adapted to sew a short seam and then come to rest, the combination with stitch-forming mechanism including a needle, of driving mechanism for the machine comprising a driving belt, a fast pulley from which the machine is operated and a loose pulley, means to shift the belt from the fast to the loose pulley at the end of the sewing operation, a thread cutter, means to actuate the same by the loose pulley at the end of the sewing operation to cut the needle thread, means to hold the cut end, and means to actuate the cutter at the beginning of the sewing operation.

10. In a sewing machine having in combination a work clamp, stitch-forming mechanism, driving mechanism for the machine comprising a driving belt, a fast pulley from which the machine is operated, and a loose pulley, means to shift the belt from the fast to the loose pulley at the end of the sewing operation, a thread cutter adapted to cut the thread between the work clamp and the work, means to actuate said cutter from the loose pulley at the end of the sewing operation, means to hold the cut end, and means for operating the thread cutter to cut the thread between the work and the thread holder at the beginning of the seam.

11. In a sewing machine having in combination a work clamp, stitch-forming mechanism, a stop motion to bring the machine to rest at the end of the sewing operation, and means controlled by the stop motion to hold the thread at the completion of the sewing, a cutter controlled by the stop motion to sever the thread between the work clamp and the work at the completion of the sewing, and means for actuating said cutter by the travel of the work clamp to sever the thread at the beginning of the seam.

12. In a sewing machine, the combination with work-holding means, of stitch-forming mechanism, a driving element for operating the stitch-forming mechanism, means to operatively connect said driving element to or disconnect it from the stitch-forming mechanism, means actuated by the driving element after it is disconnected from the stitch-forming mechanism to cut the thread.

13. In a sewing machine, the combination with work-holding means, of stitch-

forming mechanism, a driving element for operating the stitch-forming mechanism, means to operatively connect said driving element to or disconnect it from the stitch-forming mechanism, means actuated by the driving element after it is disconnected from the stitch-forming mechanism to cut the thread and to hold the cut end.

14. In a sewing machine of the type adapted to sew a short seam and then come to rest, the combination with work clamps for clamping the work, which clamps are adapted to be released automatically at the end of the seam, of an auxiliary clamping device, means operative at the end of the seam to retain the auxiliary clamping device in operative position after the work clamps have released the work, means for cutting the thread subsequent to the release of the work clamps, and means subsequently to release the auxiliary clamp.

15. In a sewing machine having a fast pulley, a loose pulley, a belt for operating said pulleys, and a belt shipper, the combination with said loose pulley, of a worm rigid therewith, a thread cutter, and means actuated by said worm when the belt is shifted from the fast to the loose pulley to actuate the thread cutter.

16. In a sewing machine having a fast pulley, a loose pulley, a belt for operating said pulleys and a belt shipper, the combination with said loose pulley, of a worm rigid therewith, a thread pull-off, a thread cutter, and means actuated by the worm when the belt is shifted from the fast to the loose pulley to actuate said pull-off and thread cutter.

17. In a sewing machine having a fast pulley, a loose pulley, a driving belt and a belt shipper for shifting the belt from the fast to the loose pulley, the combination with said loose pulley, of a worm rigid therewith, a member normally disconnected from the worm, means to operatively connect said member to the worm when the belt is shifted from the fast to the loose pulley, whereby said member is actuated by the worm, and a thread cutter actuated by said member.

18. In a sewing machine having a fast pulley, a loose pulley, a driving belt and a belt shipper for shifting the belt from the fast pulley to the loose pulley, the combination with said loose pulley, of a worm rigid therewith, a slideable member, a pin carried thereby and normally held out of engagement with said worm, means to place the pin in operative engagement with the worm when the belt is shifted from the fast to the loose pulley and a thread cutter actuated by said slideable member.

19. In a sewing machine having a fast pulley, a loose pulley, a driving belt and a

belt shipper for shifting the belt from the fast pulley to the loose pulley, the combination with said loose pulley, of a worm rigid therewith, a slidible member, a pin carried thereby and normally held out of engagement with said worm, means to place the pin in operative engagement with the worm

when the belt is shifted from the fast to the loose pulley, and a pull-off and thread cutter actuated by said slidible member.

10

In testimony whereof, I have signed my name to this specification.

JOHN KIEWICZ.
